UNITED STATES PATENT OFFICE.

PAUL HERMANN MINCK, OF BREMEN, GERMANY, AND EDWARD CARSTENSEN DE SEGUNDO, OF LONDON, ENGLAND.

APPARATUS FOR SEPARATING FIBERS FROM OTHER MATERIALS.

1,089,661.

Specification of Letters Patent.

Patented Mar. 10, 1914.

Application filed March 9, 1908. Serial No. 419,942.

To all whom it may concern:

Be it known that we, PAUL HERMANN MINCK, a subject of the German Emperor, residing at 17 Altmannstrasse, Bremen, in the German Empire, manufacturer, and EDWARD CARSTENSEN DE SEGUNDO, a subject of the King of Great Britain, residing at 231 Dashwood House, New Broad street, in the city of London, England, consulting engineer, have jointly invented certain new and useful Improvements in Apparatus for Separating Fibers from other Materials, of which the following is a specification.

This invention relates to apparatus for separating fibers from other materials such as seeds, knots, dirt or the like, and more particularly for separating fibers from the hulls of decorticated cotton seeds. It has been proposed to effect this by beating the raw material fed into a chamber or drum, by means of revolving beaters, separating the fibers from the remainder by a current of air which is drawn in with the raw material by the action of the beaters, and conveys the separated fiber from the drum into a suitable receiver.

The present invention consists in an improved apparatus of this class which is characterized by the fact that the raw material is fed into the closed drum near the periphery thereof and in such manner as to preclude as far as possible the entrance of air, while the air is drawn by means of a suitable fan into the drum through perforations in the bottom thereof and leaves it by a central tube at the top of the drum. The result of this construction is that the air currents by which the separation is effected must traverse the full length of the drum before they pass to the outlet pipe, and further, since the air and with it the separated fibers, is drawn upward from the sides of the drum toward the center while the shells or hull remains separated from the fiber are driven by centrifugal action toward the sides, being too heavy to be influenced to any appreciable extent by the inwardly converging currents, there will therefore be little or no interference with the free discharge of the separated fibers, and consequently the separation is rapidly and efficiently accomplished. This principle of action, which is characteristic of the improved apparatus, together with other features of the present invention, will be

readily understood by reference to Figure 1 of the accompanying drawings, which shows a diagrammatic vertical section of one construction of the improved apparatus, Fig. 2 being a vertical section of a slightly modified apparatus, and Fig. 3 a detail herein-after referred to.

Referring chiefly to Fig. 1 into the drum *a* extends the suitably journaled and suitably driven vertical shaft *b* carrying a nave *c* to which are fixed the beater arms *d* arranged on a helical line. These beaters may be set either to retard or accelerate the progress of the material downwardly through the drum, or some of the beaters may be set one way and some the other way. The cover *e* of the drum has a central conical extension *f* terminating in a pipe *g* in which or in communication with which is a fan, not shown in the drawing, for drawing air through the perforated sides *h* of a conical chute below the drum, and the peripherally perforated bottom *i* of the latter, as indicated by the arrows. To prevent accumulation of separated fibers on the top of the nave *c* and also to prevent eddies and increase or maintain the velocity of the air currents on their passage through the top of the drum, the nave *c* may be surmounted by a cone *k*. The feeding device consists of a hopper *l* having a spiral conveyer *m* which fits the hopper casing as tightly as possible. The worm *m* feeds the material into the drum through the cover *e* at its periphery.

In the construction of Fig. 2 the raw material is fed by suitable means not shown in the drawing, such as a screw conveyer, into the pipe *n*, whence it passes into a horizontal cylindrical casing *o* in which is fitted a rotatable feeder *p* which has a plurality of radial blades *p'* extending from the shaft to the wall of the casing, these blades dividing the casing into a number of compartments in such manner that for any position of the feeder the inlet pipe *n* is completely shut off from communication with the delivery pipe *q* thereby precluding the passage of currents of air either into or out of the separating chamber or drum *a* through the pipe *q*.

The separating chamber is preferably annular in form, as shown, the inner wall being provided with suitable bearings for the vertical driving shaft *b* on which is secured an annular nave *c'* having radial beaters *d*.

The peripheral holes or slits *i'* in the bottom of the drum, through which the air is drawn by the fan and through which also the shells or hull-remains are discharged on 5 to an inclined platform *j* formed on or secured to the supporting standard or framework of the apparatus, by which they are directed into any suitable collecting receptacles, are preferably formed as shown in 10 Fig. 3 by punching out and bending downwardly, but without separating from the integral part of the floor, portions of the sheet metal composing the floor of the drum so as to form a downwardly inclined lip on the 15 farther side of the holes or slits with respect to the direction of movement of the beaters. It will be noted by reference to the drawings that the ends of the beaters are spaced from the walls of the drum, and as a result 20 the hulls will be threshed, but not ground. The prevention of the grinding action is an important feature, in that while the hulls may be broken in the threshing action, they will not be ground to a powder, and therefore 25 fore the fiber and hulls will separate, where- as such separation would not be as effective if the hulls were reduced to a powder. It is found that with this construction of 30 outlet for the shells and inlet for the air, the outlets do not become blocked by a mass of hull-remains projected centrifugally into the opening and further the final separation of any adhering fibers is effectively accom- 35 plished by the inrushing stream of air en- countering the shells as they drop over the outer edge of the holes on to the inner lip thereof.

In operation the material is caught by the beaters as it enters the drum and is opened 40 out by them so as to enable the fibers to be carried off by the ascending air currents, while the specifically heavier portions, such as the seed cases or shells, fall finally to the bottom of the drum and are discharged as 45 before described after being subjected to a final scouring by the air currents entering the holes *i* or *i'*.

Instead of completing the separation of the fibers in a single drum as hereinbefore 50 described, the process may be carried out in stages in a number of similar drums through which the hulls are passed in series, and these drums may be fitted with floors perforated as shown or may be left more or less

open at the bottom. By this means a classification or grading of the separated fibers may be obtained. 55

Having thus described the nature of this invention and the best means we know of carrying the same into practical effect, we 60 claim:—

1. In apparatus for defibrating cotton seed hulls, the combination with an upright casing having a bottom, provided with marginal openings that constitute air inlets and 65 outlets for the discharge of defibrated hulls, of a vertical shaft extending through the bottom into the casing and terminating short of its upper end, rotary threshing beaters connected to the shaft and operating in the 70 casing, said upper end of the casing having a central tapered unobstructed uptake, and means connected to the uptake for creating an outward blast of air therethrough sufficient to produce indrafts through the bot- 75 tom openings, which indrafts are, however, sufficiently weak to permit the outflow of the defibrated hulls.

2. In apparatus for defibrating cotton seed hulls, the combination with a substan- 80 tially vertical casing having a bottom pro- vided in its marginal portions with a plu- rality of outlet openings and downwardly inclined lips extending beneath said open- 85 ings, said casing having a tapered top and a central wholly unobstructed uptake, of a vertical shaft extending through the bottom of the casing and terminating short of said uptake, rotary beaters connected to the shaft and operating in the casing, means for cre- 90 ating an uptake of air through the casing and means for feeding hulls to be defibrated into said casing and substantially prevent- 95 ing the ingress of air through said feeding means.

In testimony whereof we have signed our names to this specification in the presence of two subscribing witnesses.
